PHOTOMETER

Harold Y. Minas, Salt Lake City, Utah, assignor to Alpa
Corporation, Pleasant Grove, Utah

Filed June 8, 1970, Ser. No. 23,346

Term of patent 14 years

Int. Cl. D24—02

U.S. Cl. D16—2

FIG. 1

FIG. 2

FIG. 3

FIG. 4

FIG. 5

FIG. 6

FIG. 1 is a perspective view of a photometer showing my new design;

FIG. 2 is a top plan view thereof;

FIG. 3 is a side elevation thereof, the opposite side is substantially the same in appearance as the side shown;

FIG. 4 is a front view thereof;

FIG. 5 is a back view thereof; and

FIG. 6 is a bottom view of the photometer.

I claim:

The ornamental design for a photometer, as shown.
